ELECTRIC SWITCH

Guy H. Porter, Linwood, Pa.

Application April 7, 1938, Serial No. 200,795

7 Claims. (Cl. 200—70)

The object of the invention is to provide an electric switch particularly adapted for use in installations where the circuit control carries very heavy current; to provide a switch construction in which the circuit opening function is effected instantaneously, so that, for all practical purposes, there will be no resultant arc with its consequent deterioration of the current carrying contacts; to provide a switch of the quick make and break form in which the making and breaking functions are accomplished without danger of shock or jar to the operator's arm; to provide a switch construction in which the design makes for ready adaptation of the device to the double-throw form; to provide a device of the kind indicated in which the switch is locked either in its circuit closing position, or open position; and generally to provide a quick break, heavy current switch which is of sturdy form, unlikely to have its parts disarranged or broken under the most exacting conditions of practice, and which, for the functions to be performed, is of comparatively simple construction, so as to be susceptible of comparatively cheap manufacture.

With this object in view, the invention consists in a construction and combination of parts of which a preferred embodiment is illustrated in the accompanying drawings but to which the invention is not to be restricted. Practical application may dictate certain changes or alterations and the right is claimed to make any which fall within the spirit of the invention.

In the drawings:

Figure 1 is an elevational view of the improved switch looking at that end in which the movable contact actuating arm is carried, this view showing the switch in one of its circuit closing positions.

Figure 2 is a view similar to Figure 1, showing an intermediate position of the actuating handle in effecting circuit opening position of the switch, a later position of the actuating handle being indicated in dotted lines.

Figure 3 is a view similar to Figure 1 but showing the switch in open position, a later position of the actuating handle being indicated in dotted lines.

Figure 4 is a view similar to Figure 1 but showing the switch in the reverse position, the next position of the actuating handle to effect neutral or open position being indicated in dotted lines.

Figure 5 is a transverse sectional view through the combined handle and arm shaft in the plane of the pin and slot connection between elements thereof and showing the relative positions of ele-

ments when the handle is in the position A indicated in Figure 1.

Figure 6 is a view similar to Figure 5 with the elements in the relative positions assumed when the handle is in the position B indicated in Figure 2.

Figure 7 is a view similar to Figure 5 but indicating the positions of the shaft elements when the handle is in the position C indicated in Figure 3.

Figure 8 is a view similar to Figure 5 but showing the relative positions of the shaft elements when the handle is in the position D indicated in Figure 3.

Figure 9 is a view similar to Figure 5 but showing the relative positions of the shaft elements when the handle is in the position E of Figure 4.

Figure 10 is a view similar to Figure 5 but showing the positions of the shaft elements when the handle is in the position F of Figure 4.

Figure 11 is a sectional view on the plane indicated by the line 11—11 of Figure 4.

Figure 12 is a sectional view on the plane indicated by the line 12—12 of Figure 11.

Figure 13 is an end elevational view looking at the opposite end from that shown in Figures 1 to 4 inclusive.

Figure 14 is a sectional view on the plane indicated by the line 14—14 of Figure 13.

If the invention be constructed to operate merely as a single-throw switch, there will be but one set of fixed contacts 20 but if constructed to be of the double-throw form, there will be a corresponding oppositely disposed set of contacts 21. The contacts 20 or 21 may be engaged by the movable contacts 22 which are shifted into engagement with the fixed contacts by imparting angular or turning movement to the shaft 23, the latter being journaled in the cross bars 24 which are elements of the main frame and span the side-plates 25 in addition to the transverse bars 26 and 27.

The fixed contacts have leaf supports 28 of laminated form but of spring metal of high electrical conductivity, so that the fixed contacts 45 may yield slightly when engaged with the movable contacts. The leaf supports are secured to the insulating plates 29 by means of cap screws 30 or acceptable fasteners to which the the conducting leads of the circuit to be controlled are connected.

The insulating plates 29 are supported in the frame between the side plates 25 and span the transverse bars 24 and 27.

The movable contacts 22 consist of strips of

high conductivity material clamped to arms 31 by means of bolts 32, these contacts being arranged in divergent relation and backed with an acceptable cushion 33, consisting of wedges of metal or similar material, since the movable contacts, in engaging the fixed contacts, are subjected to a considerable shock and constant operation would bend them, were it not for the backing members 33. The arms to which the movable contacts are attached are clamped to the shaft 23 but around insulating bushings 34, the shaft being cross sectionally angular or square at the points where it receives the arms and the clamps consisting of complementary elements of which one is formed as an integral part of the arm, as indicated at 35, and the other as a separable member 36 secured to the member 35 by means of bolts 31.

While the shaft 23 is cross sectionally angular in the arm receiving zone, it has circular journals to provide for its rocking movement in the bearings in the cross rods 24 and at one side of the frame the journal is extended to receive the hub 38 of a kick-over arm 39 lying in a common plane with the arms 31, the kick-over arm being formed with a yoke 40 extending above the plane of the axis of the shaft 23 and having its horns 41 arranged generally in convergent relation. Rocking movement to the shaft 23 is imparted through the kick-over arm 39.

Movement of the kick-over arm is initiated by the lever 42 which is carried on a shaft 43, journaled in the transverse bars 26, the resistance arm of the lever 42 carrying a roller 44 for engagement with the horns of the yoke to start kick-over arm movement after release of the yoke from its latch, the yoke being susceptible of being latched in either of the contact engaging positions of the arms 31. The latches consist of bars 45 provided with lateral lugs 46, the bars being pivoted, as indicated at 47, on the members 35 on the ends of the latter and being provided at the ends remote from the pivotal mounting with screws 48. The bars 45 are yieldingly impelled toward the yoke by means of springs 49 and the screws 48 project into the area bounded by the inner peripheries of the horns 41, the lugs 46 following the outer edges of the horns until the yoke is in such position that the lug of one bar will engage underneath the yoke on the inclined lug engaging face 50 with which the yoke is provided at each side. Of course when a lug engages the lug engaging face 50, the movable contacts 22 are engaged with one set of fixed contacts and there is a camming action tending to increase the engagement of the fixed and movable contacts. The screws projecting into the area bounded by the yoke horns, are in positions to be engaged by the lever 42 when the latter is rocked. A spring 51 is connected terminally to the extremities of the force arm of the lever 42 and the free end of the kick-over arm 39 and is stretched as the lever 42 moves, passing the axis of the shaft 43 and contracting on the opposite side of the shaft. The spring 51 is the means for accomplishing the quick movement of the movable contacts toward and away from the fixed contacts. Kick-over arm movement does not begin until the release of the lug from the lug engaging face of the yoke and this is accomplished by the lever 42 engaging the screw 48 in the bar carrying the engaged lug.

The shaft 43 is equipped for manual operation and to this end there is provided a hand lever 52 terminally formed with a hand grip

53. The lever 52 is not directly connected with the shaft 43 but is carried on the extremity of a smaller shaft 54 which telescopes the shaft 43, entering a bore in the latter. A certain amount of relative angular movement is provided between the shaft 43 and hand lever shaft 54, so that the hand lever may be moved a slight amount without imparting any rocking movement to the shaft 43. To this end the shaft 43 is provided with a slot 55 following the circumference of the shaft and the necessary angular extent, this slot being traversed by a pin 56 extending radially from the shaft 54.

The purpose of this pin and slot construction is to make it possible for the hand lever 52 15 to be moved a slight distance to effect latch release, there being two latch members cooperating with the arm 55' to retain the shaft 23 in an intermediate or neutral position for the contacts 22—that is, where neither will engage either 20 of its companion fixed contacts 20 or 21. The arm 55' is carried by and secured to the shaft 23 at the end remote from the kick-over arm 39 and is terminally provided with a latch receiving tongue 56'. The latch construction consists of 25 reversely arranged latch levers 57 and 58 pivotally mounted, as indicated at 59, on ears 30 pendant from one of the cross bars 27. Pull members 60 and 61 are provided for the latch levers 57 and 58 respectively and are slidably mounted 30 in guide sleeves 62 secured on one of the cross bars 24. The pull members 60 and 61 are parallel where they are mounted in the guide sleeves 62 and thereabove, but below the guide sleeves, diverge so that their lower extremities may be 35 connected with the extremities of the force arms of the latch levers 57 and 58. Springs 63, tensioned between anchor pins on the members 25 and the points of connection between the pull members and the levers 57 and 58, tend to keep 40 the pull members in their lowermost positions and the latch levers in their elevated or normally horizontal positions which are insured by the force arms of the latch levers engaging abutments 64 mounted on the members 25. 45

The latch levers are formed with nose portions 65, relatively reversely disposed and of gradually increasing width, so that their free extremities are narrower than the levers with their rear portions exceeding the levers in width to 50 provide shoulders 66.

The levers overlap at the nose portions, so that the shoulders 66 are spaced a distance sufficient to define a slot in which the tongue 56' of the arm 55' is received. In such a position, the shaft 23 is retained in a position where the contacts 22 are at the neutral point, or intermediately between fixed contacts 20 and 21. 55

The latch levers are released from engagement with the tongue 56' of the arm 55' through the instrumentality of the hand lever 52 which is provided with divergent ears 67 in which are mounted screws 68 in obstructing relation to which are ears 69 formed as lateral extensions of the pull members 60 and 61. 65

In the operation of the invention, let it be assumed that it is in the circuit closing position indicated in Figure 1 with the movable contacts 22 in engagement with the fixed contacts 21. In this position, the lever 42 is swung over on 70 that side on which it will overhang the fixed contacts 21 and the spring 51 will be subjected to its minimum tension. The movable contacts will be locked into engagement with the fixed contacts because of the lug 46 on the bar 45 en- 75

gaging the inclined face 50 of the yoke 40. In this position of the parts, the pin 56 will be at one end of the slot 55 by reason of the downward pull on one of the pull members serving to elevate the hand lever until the pin assumes such position. 5 In moving from the position shown in Figure 1 to the neutral position, the hand lever 52 will be moved to the left and in this movement the pin 56, abutting the end of the slot 55, will cause the shaft 43 to be turned and with it the lever 42, which will swing in an arc until its resistance arm impacts that end of the screw 48 invading the area defined by the horns of the yoke 40. Continued movement of the lever 42 and with it 10 the lever 52, will result in forcing the bar 45 outwardly and withdrawing the lug from underneath the yoke 40. Thereafter, the roller 44 will traverse the inner edge of the right hand horn 41 and will start the kick-over arm 39 to the left, 15 the spring 51 being stretched in the operation, as clearly shown in Figure 2. After the spring passes the axis of the shaft 43, it can contract on the left hand side of the shaft and in doing so will draw the kick-over arm 39 to the left and 20 with the latter the shaft 23 and the arm 55'. 25 The tongue 56' on the latter will then engage the inclined edge of the nose of the latch lever 57 and depress the resistance arm of the lever until the tongue impacts with the shoulder 66 of the 30 nose portion of the lever 58, when the tongue will be in a position where the latch lever 57 can return to its former position and the shaft 23 will be locked with the contact carrying arms 31 in central or neutral position, as shown in Figure 35. 3. But locking of the shaft 23 against locking movement by the latch pawls, also locks the kick-over arm and its associated yoke and the roller 44 of the lever 42 bearing against the inner edge of the right hand horn of the yoke, the 40 lever is precluded from further movement to the left. But the hand lever 52, however, has limited angular movement by reason of the pin and slot connection 55—56. The parts could be returned to the positions indicated in Figure 1 by swinging the hand lever to the right as viewed 45 in Figure 3.

But let it be assumed that the reverse position from Figure 1 is to be obtained. The hand lever 52 is depressed to the position shown in dotted lines, or the position D, indicated in Figure 3, 50 where the pin 56 will be at the opposite end of the slot 55 than formerly. In this position, the lifter screw 68 will engage the ear 69 of the pull member 60, depressing the resistance arm of the latch lever 57 which will withdraw its shoulder 55 66 from obstructing position to the tongue 56' of the arm 55'. The kick-over arm 39 can then swing to the left and by similarly rocking the shaft 23 engage the contacts 22 with the contacts 20. But this rocking of the yoke allows the roller 44 to traverse the inner edge of the horn 41 further and therefore permit further left hand swing of the lever 42, when the spring 51 will be contracted to the same length as indicated in 60 Figure 1 but on the opposite side of the device. 65

The slot and pin connection 55—56, aside from permitting sufficient hand lever movement to effect latch release, also provides for sufficient relative angular movement between the shaft 70 43 and shaft 54 to permit shifting of the movable contacts without shock to the arm of the user.

The invention having been described, what is claimed as new and useful is:

75 1. An electric switch comprising fixed and

movable contacts, a rock shaft supporting the latter, a manually actuatable rock shaft, a lever carried by the manually actuatable shaft, an arm carried by the first said shaft and having a yoke operatively connected with the resistance arm of said lever, a spring tensioned between the extremities of the lever and the arm, so that upon rocking of the second said shaft the movable contacts will be moved toward and away from the fixed contacts, and locking means for retaining the movable contacts in engagement with the fixed contacts and provided with means whereby they may be released by said lever.

2. An electric switch comprising fixed and movable contacts, a rock shaft supporting the latter, a manually actuatable rock shaft, a lever carried by the manually actuatable shaft, an arm carried by the first said shaft and having a yoke operatively connected with the resistance arm of said lever, a spring tensioned between the extremities of the lever and the arm, so that upon rocking of the second said shaft the movable contacts will be moved toward and away from the fixed contacts, and locking means for retaining the movable contacts in engagement with the fixed contacts and provided with means whereby they may be released by said lever, the locking means having a terminal screw extending into the area defined by said yoke and the lever having its resistance arm engageable with said screw and provided with a terminal roller traversing the yoke.

3. An electric switch comprising fixed and movable contacts, a rock shaft carrying the latter, a second rock shaft above the first, a lever carried by the second rock shaft, an arm carried by the first rock shaft and having a yoke formed with horns arranged at all times in embracing relation to the resistance arm of the lever, a spring tensioned between the remote extremities of the lever and the arm, and a hand lever operatively connected with the second said rock shaft, the resistance arm of said lever upon turning movement of said second rock shaft engaging a horn to initiate rocking movement to the first said rock shaft.

4. An electric switch comprising fixed and movable contacts, a rock shaft carrying the latter, a second rock shaft above the first, a lever carried by the second rock shaft, an arm carried by the first rock shaft and having a yoke formed with horns arranged at all times in embracing relation to the resistance arm of the lever, a spring tensioned between the remote extremities of the lever and the arm, a latch member spring impelled toward the yoke and having a releasing member invading the area defined by the yoke when the latch is in engaged position, and a hand lever operatively connected with the second said rock shaft to manually effect rocking of the same, the resistance arm of the lever being engageable first with the latch releasing member to release the latch and thereafter with a horn of the arm to initiate rocking movement of the first said rock shaft.

5. An electric switch comprising fixed and movable contacts, a rock shaft carrying the latter, a second rock shaft above the first, a lever carried by the second rock shaft, an arm carried by the first rock shaft and having a yoke formed with horns arranged at all times in embracing relation to the resistance arm of the lever, a spring tensioned between the remote extremities of the lever and the arm, and a hand lever connected with the second said rock shaft to impart

angular movement to the same when the resistance arm of the lever engages a horn of the yoke to initiate rocking movement of the second rock shaft, the hand lever having a limited angular movement relative to the second said rock shaft to preclude hand shock in the completion of the rocking movement of the second said rock shaft.

6. An electric switch comprising fixed and movable contacts, a rock shaft carrying the latter, a second rock shaft above the first, a lever carried by the second rock shaft, an arm carried by the first rock shaft and having a yoke formed with horns arranged at all times in embracing relation to the resistance arm of the lever, a spring tensioned between the remote extremities of the lever and the arm, a latch engageable with the yoke for retaining the first said rock shaft in the position where the fixed and movable contacts are engaged, latching means for retaining the rock shaft in a position where the fixed and movable contacts are separated, and a hand lever operatively connected with the second said rock shaft and having limited angular movement relative to the latter, the hand lever having means for releasing the last said latch upon relative movement between it and the second rock shaft, and the first said latching means being releasable by the resistance arm of said lever prior to its engagement with a horn of the yoke to initiate

rocking movement of the second said rock shaft.

7. A double-throw electric switch comprising oppositely disposed fixed contacts, a movable contact selectively engageable with either of the fixed contacts, a rock shaft carrying the latter, a second rock shaft paralleling the first, a lever carried by the second rock shaft, an arm carried by the first rock shaft and having a yoke formed with horns arranged at all times in embracing relation to the resistance arm of the lever, a spring tensioned between the remote extremities of the lever and horn, a pair of latch members arranged in overlapping relation to define a recess, an arm carried by the first said rock shaft and having a terminal engageable in said recess when the second said rock shaft is in a position where the movable contact is intermediate between the fixed contacts, and a hand lever carried by the second said rock shaft and having limited angular movement relative to the latter, the hand lever having means to trip either of said latch members to release the engaged arm when moved relative to the second rock shaft and the lever carried by the second rock shaft being engageable with a horn of the yoke to initiate rocking movement of said rock shaft when the movable contact is engaged with a fixed contact.
